UNITED STATES PATENT OFFICE

HARRISON B. WALTER, OF CHICAGO, ILLINOIS, ASSIGNOR TO CONTAINER CORPORATION OF AMERICA, OF CHICAGO, ILLINOIS, A CORPORATION OF DELAWARE

CONTAINER

Application filed April 29, 1931. Serial No. 533,757.

The present invention relates to containers and more particularly to containers for use in the shipping, displaying and dispensing of foodstuffs in bulk.

One object of the invention is to provide a container of corrugated or fibre board to be used in the shipping of cookies, wafers, crackers and the like, which will be adaptable for use with the auxiliary dispensing covers now commonly employed in retail stores for this type of product.

A further object is to provide a container embodying the above characteristics and having an integral cover thereon so correlated with the size of the container as to readily permit the assembly of the container with such auxiliary dispensing covers in a neat and effective manner while the container is in use in a retail store, without, however, injuring such cover or rendering the box unfit for further use.

To these and other ends of the invention resides in certain improvements and combinations of parts, all as will be hereinafter more fully described, the novel features being pointed out in the claims at the end of the specification.

In the drawings:

Fig. 1 is a fragmentary perspective view of one embodiment of the invention;

Fig. 2 is a perspective view of the container having an auxiliary display cover assembled therewith; and

Fig. 3 is a fragmentary perspective view of a modified form of the container and showing a different arrangement of the cover member relative to the container.

Similar reference numerals throughout the several views indicate the same parts.

The present invention, as disclosed, comprises essentially a container having a bottom and four side walls, certain of which have integral portions hinged thereto to form a top closure, and one of which hinged portions is substantially longer than the adjacent side wall of the container.

Referring more particularly to the drawings, there is shown at 5 a container embodying one form of the present invention. The container 5, which is preferably formed

of corrugated or fibre board, of suitable weight and thickness, comprises a bottom wall 6, side walls 7, 8, 9 and 10 and integral portions 11 and 12 hinged to the side walls 7 and 8, respectively, and forming, when the box has been set up, a top closure 55 therefor.

As the metal dispensing and display covers now commonly in use have become substantially standardized throughout the trade, it is, of course, necessary, in providing a carton for use with these covers, to proportion the carton to the proper size to cooperate with the dispensing covers. Also the demands of the trade generally require the use of a container which is considerably shorter in height than the width of the top of the container. Therefore, it is highly desirable to provide a carton with an integral top closure so formed that it will not interfere in assembling the container with a standard dispensing cover and may merely be folded back to permit the assembly of the box with such a cover and, at the same time, permit the containers to be readily received in the ordinary racks generally provided for this purpose. Further, the closure members should be adaptable to being assembled with the display cover without mutilating the container in any way or rendering it unfit for further use.

To this end the integral closure portion 12 is scored along a line spaced from the free edge thereof, the score line being indicated at 13, to form two sections, 12a and 12b. 85 This score line is preferably so placed with relation to the width of the portion 12 as to make the section 12a of a width equal to the height of its adjacent side wall 8. The hinged portion 11, on the side wall 7 is preferably relatively short, as shown, unless it is desired to provide a double thickness of material in the top closure, in which event said portion 11 may be formed in the same manner as portion 12.

In the use and operation of the present invention, the blanks for the container will be cut and scored at the box factory and shipped to the packer in knock down condition. The packer will set up the boxes,

fill them and secure them in any suitable manner, as by means of gummed tape. If desired the ends of the top closure members may be stapled to the upper flanges of the 5 end walls. Upon receipt of the package by the retailer the gummed tape or other securing means is removed and the portions 11 and 12 are swung upwardly to open the box, and then downwardly against their respective side walls 7 and 8. The section 12a, being substantially congruent with its adjacent side wall 8, it will lie along said wall and the section 12b will preferably be placed beneath the container adjacent the bottom wall 6 15 and will be held in such position by placing the container in a stand or rack. Obviously, if desired, the short section 12b of the portion 12 may be folded to lie between the section 12a and the side wall 8 (see Fig. 3) and 20 will be snugly held in such position by the pressure of the section 12a thereagainst when the auxiliary cover has been placed on the box.

When the portions 11 and 12 have been so 25 folded against their respective side walls, a metal auxiliary dispensing cover 14 will be placed on the container, as shown in Fig. 2. When the container is formed of resilient material such as corrugated or fibre board, 30 a considerable amount of pressure will be exerted against the flanges 15 of the dispensing cover, thereby holding such cover securely in place on the container and effectively preventing accidental dislodging 35 thereof.

Fig. 3 illustrates a modified form of the invention. In this form, the narrow side walls (or ends) of the container are formed substantially flush with the side walls 20, 40 20. For this purpose there is provided a pair of integral flaps 21, 21 on the ends of the walls 20, 20 and a flap 22 on the bottom wall of the container, the flaps 21, 21 being secured to flap 22 in any desired manner as 45 by means of rivets or staples. One wall 20 is provided with a narrow marginal closure flap 23 and the opposite wall 20 is provided with a closure member 24 formed in two sections 24a and 24b, separated by a score 50 line 25. An alternative manner of disposing the edge section 24b with relation to the container is indicated, this portion being bent back substantially parallel to the section 24a and lying flat against side wall 20 55 of the container. The position of the score line 25 is such that, when the section 24b is folded back upon the section 24a, the closure will not project substantially beyond the lower edge of the wall 20.

60 From the foregoing it is apparent that there is provided a paper board container which is inexpensive to manufacture; can be shipped in a knock down condition; is easily and quickly set up by a simple operation; 65 and, when set up, provides a serviceable,

light weight, strong construction, ideally adapted to the purposes heretofore described. Due to the efficient form of the closure member and its relation to the container, it is obvious that the container may 70 be opened and prepared for dispensing purposes by merely folding the main closure against its adjacent wall, and allowing the edge section thereof to project either below the bottom, as shown in Fig. 2, or allowing it to project upwardly along the adjacent side wall, as shown in Fig. 3.

75 While the present description sets forth a preferred embodiment of the invention, numerous changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A container having a bottom and four 90 side walls, an integral hinged portion on one side wall adapted to form a top closure, the dimension of the container at right angles to the side wall to which the closure is hinged being substantially greater than the height of said wall, and the corresponding dimension of the closure being no greater than the said dimension of the container, the free edge of the closure terminating adjacent the upper edge of the container opposite the hinge, said hinged portion being suitably scored along a line substantially parallel to the hinge to provide two sections, the inner section adjacent said side wall being substantially congruent therewith, whereby the hinged closure portion, when swung upward to open the container, may be folded around the outside thereof to lie substantially flat along said side wall and the bottom.

100 2. A container formed of resilient paper board adapted for use with a dispensing and display cover having depending flanges on its sides, said container providing a bottom and four side walls, an integral hinged portion on one side wall adapted to form a top closure, the dimension of the container at right angles to the side wall to which the closure is hinged being substantially greater than the height of said wall, and the corresponding dimension of the closure being no greater than the said dimension of the container, said hinged portion being suitably scored along a line substantially 105 parallel to the hinge to provide two sections, the inner section adjacent said side wall being substantially congruent therewith, whereby the hinged closure portion, when swung upward to open the container, may be folded around the outside thereof to lie 110

115 120 125 130

substantially flat along said side wall and the bottom, the horizontal dimension of said container at right angles to the hinge of the closure being less than the corresponding spacing of the depending flanges on the dispensing and display cover by an amount approximately equal to the thickness of at least one layer of the material from which the box is made, whereby, when the closure is folded against its attached wall and the dispensing and display cover placed on the container, the latter will be frictionally held in place on the top of the container due to the tendency of the fibre cover to move away from its attached wall.

3. A container having a bottom and four side walls, an integral hinged portion on one side wall adapted to form a top closure, the dimension of the container at right angles to the side wall to which the closure is hinged being substantially greater than the height of said wall, and the corresponding dimension of the closure being no greater than the said dimension of the container but greater than the height of said wall, said hinged portion being suitably scored along a line substantially parallel to the hinge to provide two sections, the inner section adjacent said side wall being substantially congruent therewith, and the outer section being of less width than the inner section, whereby, when the hinged closure is swung upward to open the container, the inner section of the closure is adapted to be disposed substantially parallel with its attached side wall and the outer section is adapted either to be folded back upon the inner section to lie against said side wall, or to lie beneath the bottom of the container, and a flap portion hinged to the side wall adjacent the free edge of the closure.

Signed at Chicago, Illinois, this 27th day of April, 1931.

HARRISON B. WALTER.
